CLAIM

We claim the ornamental design for veterinary syringe, as shown.

DESCRIPTION

FIG. 1 is a first side view of a veterinary syringe according to an embodiment of the invention.

FIG. 2 is a top view of a veterinary syringe according to an embodiment of the invention.

FIG. 3 is a second side view of a veterinary syringe according to an embodiment of the invention.

FIG. 4 is a bottom view of a veterinary syringe according to an embodiment of the invention.

FIG. 5 is a front view of a veterinary syringe according to an embodiment of the invention.

FIG. 6 is a back view of a veterinary syringe according to an embodiment of the invention.

FIG. 7 is a first perspective view of a veterinary syringe according to an embodiment of the invention; and,

FIG. 8 is a second perspective view of a veterinary syringe according to an embodiment of the invention.
